CARRYING CASE FOR KEYS AND DRIVER'S
LICENSE

Lawrence F. Otten, Fort Thomas, Ky.

Application April 10, 1947, Serial No. 740,513

4 Claims. (Cl. 70—456)

1

My application relates to the provision of a carrying case for a set of keys such as those pertaining to an automobile, and which may also be used to hold a driver's license.

One of the objects of the invention is the provision of a case wherein a plurality of keys may be carried in the smallest possible space and preferably in nested relationship so that the case itself may be made very small and very convenient to carry in the pocket.

Another object of my invention is the provision of a case which may be operated entirely by one hand, in opening the case, removing a selected key for use, replacing the key, and closing the case.

Another object of the invention is the provision of a case containing a plurality of keys but acting in one-hand operation to select and present for use that key which has been chosen as the one most frequently desired for use. In this connection it is also my object to provide a case from which another or a different key may be selected as desired, still in one-hand operation.

Yet another object of the invention is the provision of a key case, which, while inexpensive, will be decorative and pleasing in appearance.

Yet another object of the invention is the provision of a case adapted to be left in connection with the keys during periods of use thereof.

Ancillary objects include the provision of novel and less bulky means for mounting keys in connection with cases.

These and other objects of my invention, which will be set forth hereinafter or will be apparent to one skilled in the art upon reading these specifications, I accomplish by that construction and arrangement of parts of which I shall now describe certain exemplary embodiments. Reference is made to the accompanying drawings wherein:

Figure 1 is a perspective view of one type of my key case in open position.

Figure 2 is an elevational view of the back or hinge side of the case.

Figure 3 is a plan view of the blank for a frame device which I may use inside my case.

Figure 4 is a plan view of the frame with the parts bent into final operative position.

Figure 5 is a partial plan view of the case in open position with one key retained therein and another presented for use.

Figure 6 is a perspective view of the closed case with a key presented for use.

2

Figure 7 is a partial perspective view of the case with both keys in the inside position.

Figure 8 is a plan view of a type of key connecting chain which I may use.

5 Figure 9 is an elevational view of a type of connector whereby a key may be engaged with the chain.

Figure 10 is a partial sectional view showing a key attached to a key connecting chain.

10 Figure 11 is a perspective view of another type of case in the open position.

Figure 12 is a perspective view of the same case in closed position.

15 Figure 13 is a perspective view showing open case, one key being inside and the other outside.

Figure 14 is a plan view of a key connecting chain and another type of means whereby a chain may be engaged with the key.

20 Figure 15 is a partial sectional view showing the same elements in engagement with a key.

Figure 16 is a rear elevational view of a case showing a spring construction.

25 Figure 17 is a perspective view of an open case showing another type of key retaining element and anchoring means.

While the utility of my invention is not so limited, I shall describe it as a holder for keys of an automobile. In common practice the automobile is provided with two keys, one serving for the ignition and the automobile doors, and the other serving special purposes, such as the locking of the trunk, the glove compartment, and the like. The first mentioned key is the one most frequently used in the operation of an automobile.

30 While my case may be constructed to hold a larger number of keys, I shall describe it in a form designed to hold the two keys just mentioned.

35 In the practice of my invention I provide a hinged case consisting of a top and bottom, spring actuated to the closed position. The dimensions of the case are made as small as is consistent with the acceptance of the keys, preferably in nested position. In this way the case may be made very small and convenient to carry in the pocket.

40 Referring to Figure 1, I have shown a metal bottom portion 1, and a metal top portion 2, both of tray shape, articulated together by a hinge construction 3. The hinge construction is interrupted to provide space for a coiled spring 4 and, as shown in Figure 2, the ends of this coil 45 spring engage rear portions of the base and top.

as at 5 and 6, urging the case to the closed position. At points marked 7 and 8, I prefer to turn inwardly or indent the edges of the case slightly to provide means for engagement by the thumb or thumb nail, so that the case may be opened against the tension of the spring in a one-hand operation. End portions of the case are notched as at 9 to provide a passageway for the key-retaining chain and permit closing of case with one or more keys in the outside position.

In the bottom of the type of case thus far described, I preferably employ a frame member 10a of metal. The blank for this frame member is shown in Figure 3. It comprises side bar portions 10 and 11 and end bar portions 12 and 13. At one end of each of the side bar portions I have shown ears 14 designed to be bent into anchoring means for key retaining chains. A spring finger 15 is made integral with the side bar 10 and projects toward the opposite side bar 11.

In Figure 4 I have shown the blank formed into final shape. The side bars 10 and 11 have been bent at right angles to the plane of the blank, and the ears 14 have been formed into the aforesaid anchoring means for a ball-type chain. The frame member 10a is placed in the bottom tray-like portion 1 of the case. The side bar 10 engages beneath the hinge 3, while the side bar 11 engages beneath the indented portion 7. The frame is thus firmly held within the bottom of the case.

While other means may be used, I prefer to employ ball-type chains as my key retaining elements. These chains are pleasing in appearance and have the advantage that they do not kink. A section of such chain is shown at 16 in Figure 8.

It is necessary to provide a non-bulky means for the attachment of the chain to the key. One way of accomplishing this is through the use of a dome-shaped member 17 shown in Figure 9. This member has a lower peripheral flange 18 and is cut, as at 19, so that a chain may be engaged with it by positioning one of the balls inside the dome-shaped body, with a ball connecting means passing through the slot 19. When this engagement has been effected, a washer 20 shown in section in Figure 10 may be slipped over the chain, whereupon the chain may be passed through the perforation in a key 21. In this way I have provided a connector which is not substantially greater in dimension than the thickness of the key plus the thickness of the chain.

When a key has been fastened to a chain in this fashion, the other end of the chain may be connected to one of the sockets or anchorages 14, as will be clear from Figures 5 and 7. In the first of these figures, I have shown a key 22 (which may be thought of as the key for the trunk and glove compartments) located in the bottom portion of my case and held in place by the spring finger 15. The other key 21 is shown outside the case in a position for use. In Figure 7 both keys are shown located inside the case.

With the keys in this position and the case closed, it is a simple matter to open the case and secure the key most frequently used. The thumb nail is engaged in the indentations 7 and 8, forcing the top and bottom of the case apart. The case is then further opened by the thumb and fingers, and the key 21 is thrown outside by a simple flipping motion. The top of the case may then be released by the fingers whereupon the spring 4 will act to close it, leaving the key 21

outside, its chain 16 passing through one of the notches 9 in the case edges. This permits the case to close as shown in Figure 6, with the key 21 outside and in a position for use.

5 My case may also be employed to hold such articles as a driver's license or the like. This, when folded to a proper size to go inside my case, may be placed beneath the key 22 and the spring finger 15. For protection it may be covered, if 10 desired, with a sheet of celluloid, acetate sheeting or the like. It will be retained in the case, until withdrawn for use, by the spring finger 15, whether or not the key 22 is in the position shown in Figure 5. Normally the key 22 is also retained by the spring finger 15, so that the flipping motion practiced when opening the case is effective only in bringing the key 21 into the outside position for use. My key case is thus well adapted for the selection of the desired key in the dark or 15 in conditions of insufficient illumination. The key 21 is the one most frequently desired; but should the key 22 be desired, it may readily be disengaged from the spring finger 15 after the key 21 has been flipped out of the case and is 20 therefore out of the way. All of this may be done in darkness.

By varying the dimensions of my key case it may be made to contain a larger number of keys, and spring fingers similar to 15 may be provided 25 for all of them except the one most frequently used.

In Figures 11 to 15 inclusive I have shown another form of key case designed for minimum dimensions. I have provided a metallic bottom 30 23 and a metallic top 24 articulated together by means of hinge 25. The edges and corners of the top and bottom members are rounded for appearance and convenience. A coiled spring 26 surrounds the pintle of the hinge and has ends 35 engaging the rear side edges of the cover member 24 and bottom member 23. A second spring 26a is arranged coaxial with the first. It has an end portion engaging the rear side edge of the bottom member 23; and its other end is prolonged as at 27 and lies within the bottom member 23. There it serves as the spring finger for retaining one of the keys as well as a means for retaining the driver's license and such other papers as the case may contain.

40 Anchorage sockets 28 and 29 for the key engaging chains may be fastened directly to the bottom member 23 of the case, as by soldering or riveting. Again, the front side edges of the top and bottom members of the case are rolled or turned slightly 45 inwardly, as at 30 and 31, to permit one-hand operation. The end members of the case are notched as at 32 to provide for the passage of the chains when the case is in closed position. Figure 12 shows the case in that position, while 50 Figure 13 shows it opened with one key out and in a position for use while the other key is engaged by the spring finger 27.

In Figures 14 and 15 I have shown another means for fastening keys to the respective chains. 55 The chain is indicated at 33. The final ball on one end is engaged within the body of the dome-shaped element 34, notched as at 35 to permit this engagement. A loop-shaped element 36 of spring wire has an end turned outwardly as at 70 38, and another end 37 which is formed into a ring hinged in a perforation in the element 34. When the loop-shaped wire member is passed through the hole in a key 39, as shown in Figure 15, the outturned end 38 may be engaged in another perforation near the open end of the dome-

shaped element 34. This connector is still less bulky than the one previously described and has the further advantage of being able to lie substantially in the plane of key 39.

Yet another form of case is illustrated in Figures 16 and 17. There is a top member 40 and a bottom member 41 hinged together as at 42. Again the hinge is interrupted to provide for a coil spring 43 surrounding the pintle and having end portions 44 and 45 engaging rear edge portions of the top and bottom members, and an adjacent spring 46 having an end portion 47 engaging the rear edge of the bottom member, an inner prolonged end 48 which forms a spring finger for engaging a key 49. Front edges of the case may be indented as at 50 and 51 for the purpose hereinabove described. Notches are also provided as at 52 for the passage of the key retaining means.

The case of Figures 16 and 17 is made of plastic, preferably transparent. This has the advantage of providing a structure through which the driver's license or other enclosed papers may be seen without opening the case.

Another form of key retaining means is illustrated in Figure 17. It comprises a safety pin fastener 53 for engaging the key, and wire connecting elements 54 and 55 which have heads engaged within a ball 56. The latter of these wire connecting elements has an end formed into a loop and, in the embodiment shown this loop surrounds and is held in place by the hinge pintle 57, the adjacent portion of the bottom element being notched to permit this engagement as indicated at 58. It will be noted that the illustrated key retaining means in Figure 17 is similar in form to the so-called fisherman's swivel.

Modifications may be made in my invention without departing from the spirit of it. The cases may be decorated in any way desired, and may also be made of or coated with precious metals. Having thus described my invention in certain exemplary embodiments, what I claim as new and desire to secure by Letters Patent is:

1. In combination in a key container for the purposes described, a case comprising top and bottom portions hinged together, interior means at each end of the case for the attachment of key retaining elements of a length to permit keys to be readily flipped out of said case and returned, end portions of said case being notched to permit the passage of the elements therethrough with the case in closed position, spring means normally urging the parts of said case to closed position, and a spring finger within said case extending outwardly from a wall of said case and adapted to engage a key between its lower surface and the bottom wall of said case and retain it in position.

2. In combination in a key container for the purposes described, a case having top and bottom

portions hinged together, interior means at each end of the case for the attachment of key retaining chains, end portions of said case being notched to permit the passage of the chains therethrough with the case in closed position, spring means normally urging the parts of said case to closed position, and a spring finger for engaging a key within said case and retaining it in position, said spring finger comprising a coiled spring coaxial with the spring means urging said case to closed position.

3. In combination in a key container for the purposes described, a case having top and bottom portions hinged together, interior means at each end of the case for the attachment of key retaining chains, end portions of said case being notched to permit the passage of the chains therethrough with the case in closed position, spring means normally urging the parts of said case to closed position, a spring finger for engaging a key within said case and retaining it in position, said spring finger comprising a coiled spring coaxial with the spring means urging said case to closed position, and said case having all outer edge portions of rounded conformation.

4. In combination in a key container for the purposes described, a case having top and bottom portions hinged together, interior means at each end of the case for the attachment of key retaining chains, end portions of said case being notched to permit the passage of the chains therethrough with the case in closed position, spring means normally urging the parts of said case to closed position, a spring finger for engaging a key within said case and retaining it in position, said spring finger comprising a coiled spring coaxial with the spring means urging said case to closed position, the outer edge portions of said case being of rounded conformation, and with meeting edge portions of said case opposite the spring means being indented inwardly to facilitate opening said case.
